United States Patent Office

Des. 179,321
Patented Nov. 27, 1956

179,321

ROSARY

Mary E. Sacksteder, Dayton, Ohio

Application December 12, 1955, Serial No. 39,298

Term of patent 14 years

(Cl. D45—16)

FIG. 1

FIG. 2

FIG. 3

Portions of the drawing figures are diagonally lined to indicate transparency.

I claim:

The ornamental design for a rosary, as shown and described.
